UNITED STATES PATENT OFFICE.

CHARLES W. WALKER, OF STRATFORD, AND ARIO C. WALKER, OF BRIDGEPORT, CONNECTICUT; ARIO WALKER ADMINISTRATOR OF SAID CHARLES W. WALKER, DECEASED.

TYPEWRITING MACHINE.

Application filed April 8, 1921. Serial No. 459,604.

To all whom it may concern:

Be it known that we, CHARLES W. WALKER and ARIO C. WALKER, citizens of the United States, residing, respectively, at 5 Stratford and Bridgeport, in the county of Fairfield and State of Connecticut, have invented certain new and useful Improvements in Typewriting Machines, of which the following is a specification.

This invention relates to typewriting machines. We have a number of elemental motives in view among them being the provision of a machine which is effective in action and by which visibility and silence 10 are assured and by which errors on striking on the part of an operator may be very readily corrected before printing. There are a large number of other fundamental motives in view, which with the foregoing will be 15 set forth at length in the following description of those forms of embodiment of the invention which are merely several of a large number that we have selected for illustration in the drawings accompanying 20 and forming part of the present specification. This disclosure will enable those skilled in the art to practice the invention. Obviously we are in no sense restricted thereto as we may depart therefrom in 25 many respects within the scope of the invention defined by the claims following said description. As a matter of fact the invention is broad and fundamental in character and involves we believe, certain radically new features and as observed we have, 30 in order to comply with the statutes, shown merely several of the many ways in which the invention can be carried into practical 35 effect.

Referring to the drawings:

Figure 1 is a top plan view of a typewriting-machine involving our invention, the central portion being broken out and the lateral parts brought together, a part 45 of the keyboard being removed.

Fig. 2 is a sectional side elevation of the machine, the section being taken from front to rear.

Fig. 3 is a top plan view of the forward 50 portion of said machine.

Fig. 4 is a bottom plan view with certain portions in horizontal section.

Fig. 5 is a side elevation partly in section, of the front portion of the machine. 55

Fig. 6 is a practically similar view illustrating most of the parts shown in Fig. 5 but illustrating also others, for instance the escapement.

Fig. 7 is a front elevation of what appears 60 in Fig. 6.

Fig. 8 is a side elevation of practically the complete machine with portions broken away and in section and with the frame removed.

Fig. 9 is a top plan view with the central portion broken away and the lateral 65 parts brought together, of the platen mechanism and certain adjunctive elements.

Fig. 10 is a plan view of type carriers and certain associated parts.

Fig. 11 is a side elevation of the platen 70 mechanism and associated elements for moving the platen.

Fig. 12 is a side elevation of means by which the type selector may be moved, and certain associated parts. 75

Fig. 13 is a perspective view of a group of type carriers and justifying means.

Fig. 14 is a side elevation of the platen and certain associated parts for moving the type carriers to their initial position, so the full lines showing normal positions and the dotted lines showing moved positions.

Fig. 15 is a top plan view of the structure appearing in Fig. 14.

Figs. 16 and 17 are views somewhat similar to Fig. 14 showing arrangements for rolling the projected type back into the carriers. 85

Fig. 18 is a rear view of the mechanism shown in Fig. 16. 90

Fig. 19 is a perspective view of a type carrier, selecting mechanism, and key lever.

Fig. 20 is a side elevation of platen mechanism and certain coacting parts by which the platen may be moved forward to 95 effect an impression.

Fig. 21 is a detail view in side elevation of a modification of Fig. 20.

Fig. 22 is a side elevation of a type carrier, selecting and operating mechanisms 100 showing shift key mechanism.

Fig. 23 is a transverse section on the line 23—23 of Fig. 22 showing the release of type carriers.

- Fig. 24 is a front elevation of selector moving mechanism.
- Fig. 25 is a top plan view of a type carrier.
- 6 Fig. 26 is a side elevation of the same.
- Fig. 27 is a transverse section on the line 27—27 of Fig. 26.
- Fig. 28 is a similar view on the line 28—28 of said Fig. 26.
- 10 Fig. 29 is a detail view in side elevation partly in section of the type carriers, a portion of the selector, and the alining mechanism illustrating also buffing means which does not appear in other views.
- 15 Fig. 30 is a similar view of the same parts and showing the alining mechanism as operated to aline the type by transverse pressures.
- 20 Fig. 31 is a cross section through the upper portion of a yoke representing the buffing device thereon.
- Fig. 32 is a rear elevation of the upper portion of the yoke shown in the preceding figure with the buffing device thereon.
- 25 Fig. 33 is a bottom plan view of the structure shown in said Fig. 32.
- Fig. 34 is a detail in sectional elevation of a portion of the yoke and alining member carried thereby.
- 30 Fig. 35 is an elevation as seen from the left in Fig. 34, practically the whole yoke except the cross-bar being shown.
- Like characters refer to like parts throughout the several views which are on different 35 scales.
- As we have already observed the invention according to our view, being of fundamentally new character, it is natural to be inferred that the framework by which the 40 various operative parts are sustained for the necessary action, may be of any suitable character. The same observation of course applies to other parts of the machine whether they be fixed or movable. The framework shown, is denoted by 2 and it appears practically in full in Fig. 1 and is partly shown in other views.
- The platen mechanism is illustrated in this Fig. 1 and appears also in other views 50 for instance Figs. 2, 8, 9, 11, 14, 15, 16, 17, 20 and 21. As will be clear the platen mechanism may be of any desirable nature although a cylindrical roll as 3 meets our conditions in a satisfactory manner. It 55 generally comprises a core which we find for illustration can be made of metal such as aluminum or even steel and it is usually hollow and can be therefore formed from tubing. We should note at this point that 60 one of the prime attributes present in our machine, is the noiseless action thereof and we find that by our construction we can make this platen or roller 3 of metal without the creation of any unnecessary noise or jar. Said platen or roll unlike the ordinary typewriting machine platen or core with which we are at present familiar, has no movement in the direction of its longitudinal axis it being not sustained by the familiar travelling carriage. In other 65 words it is desirably immovable in the direction of its longitudinal axis which in the present case is its axis of rotation, the platen or roll being turnable for paper feeding after the imprint for instance of a line or part of a line or anything else necessitating paper feeding. We might observe at this point although the platen or roller is immovable in the direction of its longitudinal axis which in the present instance 70 is the axis of rotation thereof, it does have, preferably a lateral motion although this may not be necessary in all cases. However, it is desirable. Obviously the lateral motion to which we have referred, of the platen, cylinder or roll, is transverse to the axes of the platen.
- There is a platen carrier and desirably as will be understood it is movably mounted. Although the platen carrier may be of any 75 convenient character, that shown for the purpose is denoted in a general way by 4. It appears in Figs. 1, 2, 8, 9, 11, 14, 15, 16, 17 and 20. As shown the platen carrier has a rocking or oscillatory motion and for this purpose it may be loosely supported by a shaft as 5, extending between the sides of the framework 2, generally below the horizontal center line and slightly back of the vertical center line thereof. The said 80 platen-carrier involves as represented two sides as 6 practically of angular or elbow form, the bodies or main portions of the sides being somewhat longer than the lower branches thereof which fit around the supporting shaft 5 desirably near the ends thereof. The bodies or main portions of the sides are provided at their upper ends, with heads or cross pieces 7 as shown for instance in Figs. 11 and 21, these heads or cross pieces extending forwardly from the sides 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940

ceive these gudgeons or journals 9 thus providing a way of effecting the rotation of the platen for line feeding, the impression being brought about ordinarily by the movement bodily of the platen.

There is an actuator for the platen, in the construction shown, by which the platen may be moved to secure an impression and this actuator may be of any suitable nature. 10 What is known in the typewriting art as a key lever such as that denoted in a general way by 10, answers our requirements. This actuator is obviously in correlation with the keyboard of the machine, and its operative 15 or finger-striking portion may be and as shown is at the upper limit of the keyboard which after the fashion, slopes downwardly and rearwardly. This operative portion of the platen actuator might be in any other 20 suitable location. The actuator shown for the purpose is denoted in a general way by 10. It appears for instance in Figs. 1, 2, 3, and 8 and involves as illustrated, the sides 11 supported for rocking motion in proximity to their rear ends, by the transverse shaft 5 and connected at their forward ends by the cross piece 12 which is the finger-operating portion of the actuator 10, and which as represented extends uninterruptedly across the front of the machine as best shown in Fig. 1. It also appears in other views for instance Fig. 20. As illustrated this actuator or platen-moving key lever 10 is not positively connected with the platen-carrier 4 although it does operate it. As shown the sides 11 of said actuator 10 have extending rearwardly from the shaft 5 the extensions 13, as best shown in Fig. 20, these extensions hugging the sides 6 of the platen 25 carrier in proximity to the axis of motion thereof or practically at the elbows of the sides 6 of the platen carrier. The full lines in Fig. 20 for instance show the platen 3, its carrier 4 and the actuator 10 in a state 30 of rest or back. It will be assumed that type has been set up and that it is desired to obtain an impression from said type. In the construction shown the procedure will be as follows.

35 The operator of the machine will strike the cross bar 12 of the actuator 10 and naturally depress it as shown by dotted lines in Fig. 20. This causes the extensions 13 by operating against the sides 6 of the platen carrier, to swing said sides forwardly as also shown by dotted lines in said Fig. 20, the platen naturally moving with its carrier so that if paper be on the platen the paper will receive the impression of the composed type 40 whether there be one or more. It will be understood that when the pressure of the finger is taken from the cross bar 12 the actuator 10 drops of its own weight or automatically, and the effect of the actuator being 45 taken from the platen carrier 4 the platen

carrier can automatically assume its initial position.

It is desirable that the platen or cylinder 3 be given a rolling motion during its travel from its retracted position to its advance or printing position and the means by which this condition is brought about may vary decidedly although those shown meet the conditions. For this purpose we have represented links 14 which appear in Figs. 18, 70 75 and 20 for instance. The upper ends of the links are shown as jointed as by pivots 15, with the cross heads 7 near the forward ends thereof, the links being jointed as by pivots 16, to the inner faces of the sides of the 80 framing 2, the links 14 being extended below the pivots 16 for a reason we will herein-after explain. By the link construction it will be clear that as the platen 3 is advanced in the manner hereinbefore described, 85 it with the paper upon it, is given a rolling motion so that the paper instead of directly striking the type or abruptly hitting it, rolls on the type. Of course on the backward movement of the platen 3 or from 90 the dotted line position in Fig. 20 to the full line position thereof, the platen is naturally given a reverse rolling motion.

The line-feeding mechanism does not in itself concern any part of our invention. It 95 may be of any suitable character although we deem it proper to briefly describe that shown for the purpose. Back of the platen or roll 3 is a pressure or feed roll 17 as shown for instance in Fig. 2, the journals at 100 the end portions of the shaft 18 extending into the hangers 19 sustained by the heads or cross pieces 7. The paper guide 20 is attached to the rear side of the strip 8. The sheet of paper or other article to 105 receive an impression is introduced after the well-known fashion between the platen 3 and the pressure or feed roller 17 and is advanced or fed forward, that is moved toward the front of the machine by turning said roll. 110 The initial introduction of the paper is accomplished by hand. During the action of the machine for line feeding, the platen 3 is rotated by a knob as 21 (Fig. 1). The knob 21 is fastened to the outer end of the 115 platen shaft 9 and has fastened to it a ratchet wheel 22 with which is associated the detent connected to the free end of the spring 24 and fastened at its butt to the lug or projection 25 on the strip or bar 8 as best shown in 120 Fig. 2. This line-feeding mechanism is quite common and therefore we have deemed it proper to give but a concise description of it.

The machine is desirably provided with a 125 plurality of type-carriers. These type-carriers are usually movably mounted and the mounting may be of any suitable nature preferably a swinging or rocking one. Type-carriers which meet our requirements 130

are denoted by 26 and they appear for instance in Figs. 1, 2, 5 and 8. Each type-carrier, and as shown they are all alike, comprises a practically segmental or arcuate 5 sheath-like body 27. From the rear end of each sheath or envelope-like body 27 there extends the arm or branch 28 also arcuate. As represented the type-carriers 27 swing on the shaft 5 to which we have already 10 referred, the arms 28 having holes or perforations through them to freely receive the shaft and thus permit the proper oscillation of the type-carriers as they are brought into operative or advance positions. 15 In Fig. 8 one of these type-carriers 26 appears in its retracted position and a similar relation is shown by full lines in Fig. 22. When in the retracted positions the free ends of the bodies 27 of the type-carriers 26 are separably or detachably associated with a support as 29 extending between the sides of the frame and which ordinarily consists of a fixed cross-bar having 20 detent devices or latches 30 which coact 25 respectively with the free ends of the bodies 27 of the type-carriers to releasably hold them in their retracted positions which they are shown as occupying for instance in Fig. 8. After a type has been selected for use 30 from the group or series on the type-carrier, the type-carrier is automatically moved from its retracted position to an advanced position, the amount of advance varying with or 35 conforming to the particular type or character selected for printing. In Fig. 11 for instance we have shown a type-carrier 26 as having been advanced not necessarily its full extent but moved away certainly from its retracted, initial or primary position. 40 In Figs. 25 to 28 we have shown in detail the body or type-carrying portion 27 of a type-carrier 26. This body has for instance depthwise through it the slots or apertures 31 to slidingly receive for longitudinal 45 movement the type 32 the heads of the type carrying the necessary characters which are to be printed and a face such as the front face bearing a like or index character and the type being held against accidental longitudinal movement for instance by spring 50 tongues or fingers 33 bearing against the shanks thereof and which can be cut if desired from the stock of the respective bodies 27. The spring tongues or fingers 55 33 effectually prevent accidental or unintentional motion of the type with respect to the carriers as they bear at their free ends against the shanks or bodies of the type. The head or enlarged ends of the 60 type and which directly bear the characters, rest when in their down positions against the respective bodies 27. Each of the bodies carries a series or group of type, the series or groups of type in the respective type-carriers being repeated. Generally and certainly 65

in this country the characters would be all upper and lower case letters and numbers together with customary punctuation marks such as are found in the ordinary standard typewriting machine.

When the group or series of type 32 on the particular carrier is in the retracted or initial relation, the heads or shoulders of the type are in exact line longitudinally of the body 27 of the particular carrier although this line in the present case is an arcuate or curved one. When a type has been selected, and we will hereinafter explain how this may be accomplished, the type thus selected is projected above this 70 line after which the carrier is freed from its retracted position and positively advanced until desirably and at such point as further advancing movement of the carrier is arrested by a proper stop. It will of course 75 be understood that the carriers are advanced different distances, the amount followed by any one of them during its advance conforming to the character which has been selected and the selected carriers in the construction 80 shown, all abut against the stop means after 85 which they are what might be considered justified in order to obtain the most efficient results.

A stop member which meets our conditions 90 is such a one as that denoted in a general way by 34 and shown for instance in Figs. 2, 11 and 13. This stop member 34 as illustrated is practically of yoke or bail form, the transverse portion 35 thereof extending 100 entirely across the machine forward and slightly below the platen 3, and having the pendant side arms 36. This stop member 34 is normally stationary yet it may be adjusted when desired by means on the framework. It will be assumed that all the type 105 in all the carriers are in their initial positions and that the carriers are advanced and we will describe how they may be herein-after. In this event the carriers would all 110 go to their extreme advanced positions. If however a type is advanced, then that type thus advanced would strike the stop member 34 or more properly the transverse portion 35 thereof and this type would be the 115 one that had been selected by the operator, so that a number of type thus selected would form a line from which an impression should be had and by the construction described on a sheet of paper carried by the 120 platen 3. We should note at this point that in the case of letters, each upper case type in each type carrier is immediately next to the corresponding lower case.

The selector of which there is desirably 125 but one between the sides of the framework 2, generally has a motion desirably between said sides for the purpose of selecting in the case of each group of type, the appropriate one of two type always immediately 130

next each other. A selector which has met our requirements is shown in Figs. 1, 5, 19 and 22, and is mounted between the sides of the framework 2 and although broadly it 5 may be considered as immovable from front to rear or vice versa, yet it does have a little movement in this direction for the purpose as we will hereinafter explain of selecting the proper one of two adjacent type 10 in the carrier.

The type selector shown is denoted in a general way by 37 and it appears for example in Figs. 2 and 5 and as represented 15 comprises a base 38, a body or flange 39 rising therefrom and a crown portion 40 which is practically in the form as represented of a curved flange extending along the body or flange 39. Between the base 38 and the crown portion 40 is a bead or flange 41. The type selector 37 carries a group of 20 selecting members 42 the number of selecting members being practically half the number of type in a type carrier for a reason that will hereinafter appear. The selecting members 42 are practically in the 25 form of pins extending through perforations in the respective bases 38, bead or flange 41 and crown portion 40, slideable when it becomes necessary to project a type 30 from a type-carrier as we will hereinafter explain, and in turn being suitably operated for such purpose. Each selecting member or pin 42 may be actuated by a suitable part to advance the same and in turn effect 35 the advance of the desired type. As the crown portion 40 is as shown upon an arc and as the body 27 of a type-carrier is also of a corresponding shape in the construction 40 illustrated, it is desirable that the head end portions of the selecting pins 42 should be 45 in arcuate form and for this reason they are made of progressively-decreasing lengths from their central one. In Fig. 2 for instance a selector 37 is under the body 27 of 50 a type carrier 26 all of the selecting members 42 being down and all the type on the carrier being in retracted positions. It will be assumed that a selecting member 42 is advanced or moved upward and we will hereinafter explain how this can be accomplished. This selecting member thus elevated will thus strike a type and thrust it 55 upward, this type being the one which has been selected by the operator of the machine. Subsequent to this the type-carrier 26 is advanced or moved toward the left in Fig. 2 and the carrier will advance until the type projected forwardly from the carrier 26 encounters the stop mechanism or 60 member 34 or the transverse portion thereof, this action being continued until a line is composed or until matter sufficient to satisfy the operator has been set up. The selecting members or pins 42 desirably have 65 upon them the stops 44 which abut against

the bases 38 when said pins 42 are in their down or retracted positions as shown for instance in Fig. 2. It will be understood that in the construction shown the selecting members or pins 42 when the type selector 70 37 is in a position to rest, are under the group of type 32 supported by the type carrier 26 under which for the time being, said type selector 37 may be. It should be understood that each pin or selecting member 42 operates with two adjacent type 32 in the type carrier. When the type selector 37 is in its back position as shown for instance in Fig. 2, the several selecting members or 75 pins 42 will be below and practically in 80 vertical line with the lower ends of what would be the lower case so that for instance if the letter a is desired, the appropriate selecting member 42 will be elevated and when it is moved a certain distance upward, 85 it will engage the butt or shank of the type a in the type-carrier 26 under which the type selector 37 is for the time being situated, and will project said a upwardly from the type-carrier 26 subsequent to which said 90 type-carrier will be moved as we will later explain. Should the upper case A for instance be desired, the type selector 37 will be moved longitudinally in the present case or toward the right in Fig. 2 so as to carry 95 what might be considered the a selecting member or pin 42 below the cap A type 32 on the type carrier 26 after which the same pin or selecting member 42 will be elevated so as to engage the base of the cap A type 100 and elevate it. Necessarily the type selector 37 is moved and any convenient means may be utilized for the purpose although that shown and now to be described, has proven satisfactory, it appearing in Figs. 105 2, 5, 8 and 22 and other views. The framing of the machine supports as shown on the upper side the guide bar 45 around which is fitted the body 46 the guide bar 45 functioning in effect as a shaft, extending 110 through the body 46 and the two parts being rigid. The guide bar or shaft has the body 46 fastened to it between the ends thereof and the shaft or guide bar 45 extends through openings in the sides of the 115 framework and has movement in the direction of its longitudinal axis for a reason that will hereinafter appear, friction being reduced by forming in the guide bar or shaft 45 several longitudinal channels or 120 grooves 47 in which anti-friction rollers or balls 48 are situated. It will be understood that on the action of the machine which has no carriage as this term is understood in the art, the body 46 is moved step by step 125 and as the type selector 37 is rigidly connected therewith it has a step by step movement transversely or crosswise of the machine. The action of this body 46 is effected through the operation of a key lever or 130

equivalent manually actuated device by which escapement mechanism is governed to obtain the desired function. The body 46 mentioned has rigidly connected with it in some convenient manner the arm 49 extending as shown upwardly from the plate 50 against which fits flatwise as represented the forward extension 51 of the type selector 37, this extension 51 having on it the pin 52 or stud which extends through a longitudinal slot 53 in the plate 50. As represented and for security, the forward extension 51 has upon it several wings 54 bent around opposite terminals of the plate 50 as best shown in Fig. 22 although it does appear in other places. In this Fig. 22 the pin 52 is shown as being at the rear end of the slot 53 so that if a type selecting member or pin 42 is elevated, a lower case type will be correspondingly elevated whereas if the type selector 37 be advanced or moved forward toward the right in Fig. 22 the selecting member or pin in question will be brought underneath an upper case type so that when the selecting member is actuated this upper case type will be moved toward printing position.

We will now describe a means for moving the type selector 37 so as to bring into action the necessary means for the selection of upper case type. In said Fig. 22 and in other views a key lever 55 is shown as a proper means for effecting the desired action of the type selector 37 this key lever also appearing in Fig. 1 for example in the neighborhood of the lower left corner of the view. It is supported for rocking or oscillatory motion on the shaft 56 extending between the sides of the framework 2. It is somewhat of elbow form and the shaft upstanding branch thereof 57 virtually of segmental form has a notch 58 to receive the lug or ear 59 on the extension 51 of the type selector 37.

Fig. 22 shows a type-carrier 26 furnished with merely two of its type 32 and in the example given it will be assumed that the type 32 at the left in Figure 22 is lower case a while that on the right is upper case A. The pin or selecting member 42 which is merely one of a number, the rest of the selecting members and the type having been omitted from this view for the sake of clearness. This selecting member or pin 42 co-acts with both of these adjacent type 42, it being near or under the lower case type or the one at the left so that it follows as a consequence that when the selecting member or pin is elevated, it abuts against the lower case a and lifts it. If the selector 37 be advanced however, or moved toward the right as shown by dotted lines in this figure, the selecting member or pin 42 will be carried under the type on the right which in the illustration is upper case A. This action of

the type selector 37 is brought about by the depression of the key lever 55 it having at its free end the key 60 to facilitate such action and this key is practically part of the keyboard of the machine as illustrated in Fig. 1. In this Fig. 22 however, we have shown the key lever 55 as depressed so as to move the type selector 37 forwardly as illustrated by dotted lines and the elevation as we have already observed of the upper case type. There is desirably associated with the key lever 55, spring means such as the spring 61, the spring in question normally holding the key lever 55 up and naturally the type selector 37 back and returning them to their back and up positions respectively after the depression of the key lever.

Naturally the selection of type to be printed is brought about through the operator of the machine and the initial action may be accomplished in any desirable manner as for instance by a group of key levers, the keys on which may be arranged after the familiar fashion, in a bank at the front of the machine. There may of course be other ways of securing this condition and as we have already observed, the invention is decidedly fundamental in character. Key levers such as 62 answer our requirements and they appear in Figs. 1, 2, 3, 5 and 8 as well as other places. They are supported for rocking motion at their rear ends in some convenient way as by the shaft 63 extending transversely of the machine near the back lower end thereof, the arms at the forward ends of the key levers being furnished with keys as 64.

The selecting members 42 may be operated to effect the action of the respective type in any convenient way, actuators as 65 answering the purpose in a satisfactory manner and as shown functioning as lifting bars. They may consist of metal strips or ribbons arranged in parallelism with each other and as shown are sustained by bearings as 66 transverse thereto and as represented extending forwardly and backwardly between the front and rear of the frame and near opposite sides respectively thereof, it being understood of course that the actuators or as they might also be considered lifting-bars 65, extending crosswise of the machine. As shown the bearings or bar 66 have in them the vertically elongated slots 67 each bar having as shown a row of such slots longitudinally thereof, the slots being arranged in co-operating pairs and each pair of slots being intended to receive the terminal portions of an actuator or lifting bar 65, the ends of the lifting bars as a matter of convenience projecting somewhat beyond the reduced ends which fit the slots extending somewhat beyond the bars as best shown in Fig. 19. It will be clear that when an actuator or lifting bar is elevated it strikes the base of the

type selecting member 42 over it and on the continuation of the motion of the type selecting member is elevated thus elevating a type. It will be understood that the number 5 of actuators or lifting bars 65 correspond to half the number of type on each type carrier.

As a convenient means for operating the actuator 65, we illustrate operating devices 10 as 68 of bail form and nested together. It will be understood that the construction in question is shown in Fig. 19 and appears in other views for instance Figs. 3 and 5. The bails 68 are arranged in a group and are 15 virtually horizontally aligned when in normal position, the rear ends of their side branches having upstanding lugs 69 notched to receive the respective actuators or lifting bars 65 which are rigidly united thereto in 20 some convenient manner. As shown the bails 68 rock or oscillate on a shaft as 70 supported by and extending between the bearings 66, it being understood of course that there is one bail 68 associated with each 25 lifting bar 65. As shown there extends from the forward cross bar of each bail 68 a link as 71 the lower end of which is connected flexibly or otherwise with the shank of the key lever associated with the bail in question. In Fig. 19 we have shown the assemblage thus set forth and the type carrier 30 as furnished with one type of the number it carries in practice. Under this type is disposed the selecting member 42 carried by the selector 36. It will be assumed in 35 this view as in the illustration given heretofore, that the type 32 is lower case a and that the key 64 bears this character lower case a. Of course in practice the key would 40 carry the upper case A as well, although we have only shown in this view what is assumed to be lower case a in type, with its associated selecting member or pin 42 which as will be understood also coacts with upper 45 case A the type for which has been omitted. On the depression of the key lever 62 through the striking of the key 64 the link 71 is pulled down lowering the forward portion of the bail 68, the rear portion thereof 50 being elevated and thus elevating the associated actuator or lifting bar 65 so that the upper edge of this lifting bar by engaging the butt of the selecting member 42 will lift it and hence the lower case a. The same 55 action is of course repeated with the other keys and key levers when they are operated. Should the selector 37 have been moved forward in the manner described, the upper case A will naturally be elevated on the depression of the key 64 in Fig. 19. The key lever 62, the bail 68 and the actuator 64 which have been operated in the illustration given by hand, are returned to their initial positions after they are freed by the 60 fingers of the operator as quite common in

the art, spring means being generally used for the purpose.

Referring again to Fig. 19, it will be understood that if the type selector 36 is advanced, the selecting member or pin 42 will 70 naturally be moved forward and under the type 32 immediately in front of one illustrated which in the illustration being made would be upper case A so that when the key lever is depressed, the same action will be 75 repeated except the upper case A type would be lifted to printing relation as distinguished from ineffective or back position.

After a type has been moved from its back or retracted position to its printing or 80 operative position, it is necessary to advance the movable body 47 for letter spacing and this advance thereof is naturally a step by step one and is controlled desirably by escapement mechanism such as that 85 which appears for instance in Figs. 1, 2, 5, 6, 7 and 22. There is supported for example by a cross bar 72 mounted between the sides of the framework 2, the casing or housing 73 which is practically coextensive 90 with the cross-bar, the latter presenting properly a part of the casing. This casing supports within it the proper number of pawls 74 separated from each other by the 95 walls or partitions 75 between which the pawls 74 are pivotally mounted as at 76, the pawls having a preponderance of weight forward of their centers of oscillation so that they can drop on to the cross-bar or bottom 76' which is their normal position, 100 yet the forward branches are free to be elevated on proper action. There may be instances where it may be desired to lift the active portions of the pawls and for this purpose there may be associated with each 105 one a lifter as 77 pivoted between the respective walls 75, there being a lifter associated with each pawl 74 and being above the rear branch thereof. When therefore a lifter 77 is properly manipulated, it will 110 swing down the rear branch or arm of its associated pawl 74 and elevate the forward branch thereof out of the path of a dog as 79'. A dog 78 extends entirely through and below the body 46 and constitutes the loose 115 dog of escapement mechanism. The dog in the present case is lifted through the action of the operator. The loose dog 78 is lifted also in the present case by the operator as we will hereinafter explain, and is returned 120 to its initial position as by the spring 79 surrounding its shank. At the side of the loose dog 78 and in proximity to the head end thereof, is a second dog such as 79' of 125 spring form, the butt of which is fastened in some convenient way to the movable body 46 and the free end of which co-operates with the pawls 74. It will be assumed that the body 46 is in its initial position which would be at the left for illustration in Fig. 130

1. The upper end or head of the loose dog 78 will be under the free forward end of the first pawl 74 while the spring dog will be in engagement at its free end against the side face of said first pawl 74. On the elevation of the pawl 74, the pawl in question will be carried free of the spring dog 79' so that the body 46 can advance and we will hereinafter describe a way of accomplishing this, until the spring dog abuts against the second pawl 74 of the series. This action occurs in spacing either between letters or words or in filling out a line.

The actuator for the loose dog 78 may be of any suitable character that shown being denoted in a general way by 80 and consisting of a plate extending entirely across the machine between the sides of the frame 2 thereof and having between its front and rear, ears or lugs 81 to receive pivots or studs 82 on the frame of the machine. To the forward end of the actuator or lifting member 80 is shown as connected the upper ends of the side branches of a bail as 83 the cross-bar or transverse portion of which extends under the key levers 62 and also under the spacing lever 84 (Fig. 7 for instance), the spacing lever being practically of yoke form. The side branches of the spacing lever 84 are sustained for rocking motion as by the shaft 63 and the sides thereof are arranged directly over the transverse portion of the bail 82 so that every time the spacing lever 84 is depressed the bail 83 will be drawn down. In Fig. 6 for instance the full lines show the escapement mechanism in the normal position or state of rest. It will be assumed that either a key lever or the spacing lever is depressed by the operator. This will pull down the bail or yoke 83 and swing downward the front branch of the actuator 80 and upward the rear branch thereof as shown by dotted lines in said Fig. 6 thus causing the rear portion of the actuator 80 to elevate the loose dog 78 and lift the pawl 74 under which it is for the time being, as also illustrated by dotted lines in said Fig. 6, so as to cause in the manner we have already noted, the movement of the body 46 to which the escapement dogs are in the construction shown directly connected.

The advance movement of the movable body 46 can be accomplished in any convenient way, weight means being shown for this purpose, it being clear that when the body 46 is freed in the manner observed it is moved forward or toward the right in Fig. 24 and for this purpose the weight 86 is shown, this weight being connected to one end of a cord, band or chain as 87, the opposite end of which is united with the body 46, the cord or band 87 as represented passing around an anti-friction roller as 88, the bracket for which is suitably

attached to the framing of the machine. This weight 86 is of a mass sufficient to advance the body 46 or move it toward the right in Fig. 24 when it has been normally freed by the escapement mechanism the motion continuing of course until the body is arrested by a pawl 74 then in its operative position. The motion of the body 46 under the action of the weight 86 is continued step by step through the action of the operator initially, until the body 46 reaches the end of its traverse, and return of the body to its initial position may be accomplished by the weight 89 which is of a less mass than the weight 86 and which as shown is united with the movable body 46 as by a cord or band 90 connected therewith and also to the body 46 and passing between its ends around a guide roller 91, the bearing or bracket of which is fastened to the opposite side of the frame 2 to that which supports the roller 88. As shown both weights 86 and 89 are sustained for rocking motion by the shaft 5 (Figs. 11, 12 and 24 hereinbefore described). The larger weight 86 of the two weights is desirably lifted at the conclusion of the advance of the body 46 so that the latter can be drawn back or returned to its primary position by the weight 89. To maintain the advancing weight 86 as distinguished from the retracting weight 89, in ineffective relation any convenient means may be provided although those shown and now to be described meet the conditions in a satisfactory manner. It will be remembered that the platen-carrier 4 which is supported for rocking motion on the shaft 5 which carries the two weights, comprises in its construction the sides 6 constituting part of the platen-carrier. A side of the frame 2 pivotally supports the elbow lever 93, the pivot being denoted by 94. The short or lower arm or branch of the elbow lever is bent or curved down at its free end as at 95 for co-action with a pin or stud as 96 on the cooperating side 6 as best shown in Fig. 12. To the upper arm of the elbow lever 93 is jointed the back end of a link 97 the forward end of which is likewise connected with the rear arm of the angle lever 98 shown as pivoted for rocking motion as at 99 to the adjacent side of the frame. The link 97 is connected with the rear branch or arm of the angle lever 98, a link as 100 being pivoted to the other arm and being likewise jointed to the weight 86. In Fig. 12 the full lines applied to the part show the weight 86 as up, the body 46 being assumed to be back, the dotted lines 101 showing the weight as having fallen or gravitated to effect in the manner hereinbefore described, the advance under the control of escapement mechanism, of the body 46. During this time the weight 86 is of course being lifted and if the weight 86 be in the position 101 the weight 89 will

be in the position 102, having been lifted through the primary influence of the descending or larger weight 86.

It will be assumed that a line of type has been set and that an impression has been made. There might be only one character or even none in the line but to make an impression it is necessary to swing the platen-carrier 4 forwardly as it is illustrated as 10 having been so swung by dotted lines in Fig. 12. When this is accomplished the stud pin 96 will apply a camming action to the lower hook branch 95 of the elbow lever 93 and will swing the upper branch 15 or body of the elbow lever toward the right in Fig. 12 and thereby through the described parts actually lift the weight 86 or return it to its primary position and as the weight 86 commences to lift, the weight 89 becomes 20 effective for imparting a return movement to the body 46 which is continued until said body reaches its initial position.

It will be assumed that type bearing the necessary characters have been advanced or 25 projected from the operative portions of the type-carriers and that the latter have been freed in the manner hereinbefore described, they swing back when thus released until the advanced type encounters a stop such as 34 30 to which we have hereinbefore referred, the transverse portion of this stop 34 being in the path of the projected type, those which may not have been projected, passing of course under the cross-bar or operative portion of 35 the stop. Co-operative with this stop member or arresting device 34 is an aliner 103 which unlike the stop member 34 is not stationary but on the contrary has in the present case a swinging movement and as 40 shown its operative portion strikes the heads of the projected type which are against the active portion of the stop member 34 so as to bring the type into exact lateral alignment distinct means being provided to 45 longitudinally align the type so that their heads or printing portions will be in exact coincidence with each other. The aliner 103 as shown is practically in the form of a swinging or oscillating bail, the side 50 branches 103* being pivoted to the sides of the framing 2, having a movement about a horizontal axis, and the transverse portion of the bail constituting the operative part of the aliner and being intended to engage 55 against the heads of the type on the carriers 26 when these heads have been arrested by the stop member 34. The aliner 103 as we have termed it may be operated in any convenient way as by the actuator 10 herein- 60 before described and shown in several views such as Figs. 1 and 2. It will be remembered that the actuator 10 has been described as being of bail form and as having sides 11 supported by the bar 12 which extends

across the machine at the top of the key-board. 65

The platen carrier 4, it will be remembered, comprises in its makeup two sides 6 surmounted by heads 7 connected in turn by a cross-bar 8. We have also alluded to 70 the fact that the cross heads 7 have pivoted to them the links 14, the pivots of the links being denoted by 15 as shown for example in Fig. 11. In addition to this the links are pivoted as at 16 to the sides of the framework 2 at horizontally alined points. To the lower ends of these links or levers 14 are jointed as by pivoting, the links 104 which are connected flexibly in some convenient way to the aliner 103, links as 105 80 serving as a proper means for making this flexible connection and the terminals thereof being connected pivotally respectively with the aliner 103 and links 104 as shown for example among other views in said Fig. 11. 85 It will be clear that the linkage connection described between the platen carrier 4 and the aliner 103 provides a convenient means of multiplying motion, that is to say the platen carrier 4 moves but a comparatively 90 short distance during which the platen is caused to roll over the said type as we have previously explained, and on this action the aliner 103 is swung forward or advanced from the full line to the dotted line position, having on this movement a greater range of action than the platen carrier 4. 95

After the type have been arrested by the stop 34 in the manner described, they are alined in one direction by the swinging of 100 the aliner 103, which is brought about by the depression of the key lever or actuator 10 which through the described parts advances the aliner or swings it backwardly and causes its transverse portion to press against the 105 heads of the type 32 abutting against the cross-bar 35. After the type have been acted on in this manner, the composed line is subjected to a further correcting or alining of 110 the type longitudinally, this being accomplished by the lateral movement of the cross-bar 108 which is slidably held in the sides 36 of the bail 34 and is moved to engage the bottoms of the type to bring said type to 115 their proper position, the bar 108 being moved by means of a cam as 109 which is pivoted as at 110 in the sides 36 of the bail 34, said cam having connected to it one end of the link 111, its other end being attached to the free end of the link 14. As has been 120 previously described the movement of the platen carrier 4 by the actuator 10 will cause the free end of the link 14 to oscillate and in turn will actuate the cam lever 109 which elevates or moves cross-bar 108 in the position to aline the type. The opposite oscillation of link 14 will in turn cause the cam 125 109 and link 108 to move to their initial posi-

tions. After the aliner 103 and cross-bar 108 have brought the type to their proper horizontal and lateral positions, the type is then ready for printing, and this printing is brought about by the rocking or rolling motion of the platen or roll 3. It will be remembered that the printing or impression movement of the platen or cylinder 3 is effected by the primary action of the actuator 10, this actuator being utilized to align the type as we have stated.

It will be obvious that after the line of type has made the impression through the action of the platen roll 3, it will be necessary to bring the type-carriers 26 back to their initial positions and this is accomplished properly by the means best shown in Figs. 14 and 15 it also being clearly shown in Fig. 17. The type-carriers 26 are returned to their initial position through the retracting movement of the platen carrier 4. The initial action of said retracting mechanism is accomplished when the platen is being advanced or moved to the position to obtain an impression of the type and the return of said mechanism is accomplished when the platen carrier is moved to its primary position. It will be noted that in the sides or heads 7 there are rigidly attached pins 112 which when the platen moves forward the pins 112 are caused to rotate. The pins in their rotation when they come in contact with a cam-surface 113 of a link 114 which is slidably attached to the gudgeons 9 will cause said link 114 to move forward in the slot 115 under tension of the spring 116. After the pins 112 pass over the cam-surface 113, the spring 116 causes the link 114 to retract this causing the pins 112 to enter the recess 117 of said link. During the retracting movement of the platen roll 3 the pins 112 being as before described in the recess, cause the link 114 to move with the sides 7. Attached to one end of the link 114 are the links 118 and to its lower or opposite end are attached the oscillating links 119 one end of said link being jointed to the shaft 5 and the other end to the shaft 120, this shaft going the full length of the bank of type carriers. When the link 114 is nearly in its upper position as shown by dot and dash lines, the pin 121 rigidly attached to link 114 comes in contact with the cam-surface 122, of the cam 123 which is attached to the said frame 2. This causes the link 114 to move forward again in the slot 115 freeing the pins 112 from the recess 117 and thus permitting the link 114 to return as by gravity or other means to its initial position.

It is also obvious that the type which have been projected from their carriers for impression, must be pushed back to their initial or original position and this is ac-

complished as shown best in Figs. 16 and 17, 65 by the type-roller which is denoted in a general way by 124. The type-roller 124 is composed of a roll as 125 which is attached at its outer ends to the bail-like piece 126 supported by the trunnions 127. In 70 order to roll the type back to their proper position, it is necessary that the roll must be in a low enough position to cause the type to be pushed in to the carriers 26 and on the other hand it is necessary that the 75 roll should be permanently placed in a high enough position to permit the raised type to pass over the said roll without causing the movement of the type selected. The downward movement of the roll 125 is accomplished by means of the link 128 one end of this link being pivoted at 128' to the sides of the frame 2, the link 128 being brought out of engagement with the trunnions 127 as by the connection of the link 80 129 at a pivotal point as 130 on link 128, the other end of the link 129 being slidably attached to the outer end of the link 93.

It will be assumed that a sheet of paper has been applied to the platen 3 in the manner hereinbefore described and that a line of type has been composed. As the actuator 10 is moved, the platen carrier 4 is moved forwardly thus causing the movement of the platen toward the line of type and the receipt on paper carried by the platen, by the type which rolls over the type owing to the rolling of the platen.

For sake of clearness we have deemed it unnecessary to illustrate any inking mechanism. The inking means might involve either a ribbon or a pad or might be of other character and there might in fact be instances where there might be no inking.

In Figs. 29 and 30 we have shown certain 105 of the parts of the machine and with buffing and alining mechanism. In these two views the type selector is denoted by 37' although none of the pins or selecting members such as hereinbefore described and designated as 110 42, are illustrated thereon. In the two figures however appears the carriage or travelling body 46' which is exactly like the carriage or travelling body 46 hereinbefore described and which is also given a step by 115 step movement to effect a corresponding action with respect to the type selector 37' this step by step action being brought about desirably by key-controlled mechanism. In this modification the type are carried by 120 type-carriers as 26' the type being denoted by 32'. Although the type-carriers 26' like the type-carriers 26 may be moved in any desirable manner, generally being moved from inoperative to operative positions by 125 manually-governed selecting means and as shown in Figs. 29 and 30 one of them as the one on the left both views is in its

operative position having been moved bodily on its carrier by a lifting action which has been hereinbefore described and which therefore need not be repeated. The 5 type carriers are automatically arrested on their advancing movement which is toward the left in Figs. 29 and 30. In the construction described in connection with the machine illustrated in Figs. 1 to 28 inclusive, the advancing movement of the type carriers 26 was arrested by a rigid stop as 34. Practically this same stop member appears in Figs. 29 and 30 but it is denoted by 34' and it comprises a bail made 10 up of a transverse portion 35' and side arms 36' having desirably a rigid connection with the shaft 5' on which the type carriers 26' rock. Although the operative or active portion 35' of this stop member 34' does function as a stop and is effective for the purpose, still to eliminate noise as far as practicable, we wish to arrest the advancing motion of the type-carriers 26' by buffing or yieldable stop means which as 15 shown is encountered by the type which are in operative relation as the carriers 26' swing back by gravity after they have been released. It should be well at this point to explain that between the sides of the framing there is a fixed support 29' furnished with detent devices 30' and that when any type-carrier 26' is released through the agency of the operator such 20 type-carrier advances or swings toward the left until the type therein is arrested and we have explained how this arresting can be brought about by the stop member 34', the effective portion 35' of which acts in this regard. To arrest momentarily or 25 yieldingly check the advancing motion of the carriers 26' a buffering device such as 135 is provided. This buffering device as shown comprises an enveloping portion 136 attached by one of its cheeks to the under flat side of the cross-bar 35' and which receives within it a strip as 137 of some suitable fabric such as felt, the felt strip extending beyond the enveloping portion or receiver 136 and its free end hanging 30 down slightly. When therefore a carrier as 26' is advanced, the motion is continued until the advanced type strikes the buffering portion or strip 137 which naturally arrests the further movement of the carrier and this same action is repeated with the 35 remainder of the carriers all of them being yieldingly arrested or buffed before they strike the rigid cross-bar 35'. After the stops have encountered the buffering strip 137, they are subjected to an alining action, there being ordinarily two alining pressures directed transversely of each other in order to secure as far as possible perfect alinement and which may be as hereinbefore described. With the exceptions noted the 40 structure shown in Figs. 30 to 33 inclusive is very much like that already described and in the views thus enumerated, the parts which have been hereinbefore described are therefore given the same characters together with prime marks. 45

In Figs. 34 and 35 we have shown a modified form of stop member which is denoted by 34'', this stop member being in the form of a bail rigidly supported by the shaft 110''. The shaft 110'' also supports a cam member 109'' for rocking motion the effective portion of the cam as shown being adapted to engage the under edge of the slidable member 108'' supported by the arms 36'' of the part 34'', these arms having in them elongated slots to receive the terminal portions of the element 108''. This element 108'' is engaged by the plate 140 which has hooks 141 in it, the shanks of which extend through slots 142 and engage the back surface of the part 108''. The upper side of the transverse piece 140 has a back-turned flange 143 through which are threaded screws as 144 adapted to engage the upper edge of the cross piece 108'', this flange 143 constituting the active portion of an aliner and through the operation of the screws 144 which are at the ends of the part 140 the effective width of the operative portion of the aliner may be adjusted to conform to the number of sheets on the platen. 50

What we claim is:

1. A typewriting machine comprising a platen, type, a rigid stop to hold the type in printing position, means to be yieldingly engaged by the type before they are arrested by said rigid stop, and means for securing an impression from the type when they are against the rigid stop. 100
2. A typewriting machine comprising a type-carrier provided with groups of type, a selector, and means on the selector for pushing type from each group from an inoperative to an operative position. 105
3. A typewriting machine comprising a series of movable type-carriers provided each with a group of type, the type of the respective groups being the same, a selector, means for causing the movement of the selector along the series of type-carriers, and key-operated means on the selector, for pushing the type from an inoperative to an operative position. 115
4. A typewriting machine comprising a group of movable type-carriers provided each with a group of type, the type of the respective groups being the same, a selector, manually-operable means for causing the movement of the selector along the series of type-carriers, and manually-operated means on the selector, for pushing type from an inoperative to an operative position when the selector is at a state of rest. 125

5. A typewriting machine comprising a series of movable type-carriers provided each with a group of type, the type of the respective groups being the same, a selector, 5 key-operated means for causing the movement of the selector along the series of type-carriers, and key-operated means on the selector for pushing type from an inoperative to an operative position.
- 10 6. A typewriting machine comprising a series of movable type-carriers provided each with a group of type, the type of the respective groups being the same, a selector, key-operated means for causing the movement 15 of the selector along the series of type-carriers and key-operated means on the selector, one for each two type on the selector, for pushing type from an inoperative to an operative position.
- 20 7. A typewriting machine comprising a series of movable type-carriers provided each with a group of type, the type of the respective groups being the same, a selector, key-operated means for causing the movement 25 of the selector along the series of type carriers, and key-operated means on the selector, one for each two type on the selector, for pushing type from an inoperative to an operative position, when the selector is at 30 a state of rest.
- 35 8. A typewriting machine comprising a series of movable type-carriers provided each with a group of type, the type of the respective carriers being the same, a selector, means including an escapement device, for causing the step by step movement of the selector along the series of type-carriers, and key-operated means on the selector for pushing type from an inoperative to an operative 40 position when the selector is arrested.
- 45 9. A typewriting machine comprising a series of movable type-carriers provided each with a group of type, the type of the respective groups being the same, a selector, manually-operable means for causing the step by step movement of the selector along the series of type-carriers, and key-operated means on the selector, for pushing type from an inoperative to an operative position 50 when the selector is at approximately a state of rest.
- 55 10. A typewriting machine comprising a series of segmental type-carriers each provided with a group of type, the type of the respective groups being the same, a selector, key-operated means for causing the movement 60 of the selector along the series of type-carriers, and key-operated means on the selector, for causing the movement of the type from an inoperative to an operative position.
- 65 11. A typewriting machine comprising a movable carrier provided with type, means for selecting type and for causing the movement of the type from an inoperative to an operative position while on the type-carrier, means for causing the movement of the type-carrier after the selection of a type, means for arresting the motion of the type-carrier, and yieldable means to arrest the type-carrier before it reaches the other arresting means. 70
12. A typewriting machine comprising a movable carrier provided with type, means for selecting type and for causing the movement of a type from an operative to an inoperative position while on the type-carrier, 75 means for causing the movement of the type-carrier after the selection of a type, means for arresting the motion of the type-carrier, yieldable means to arrest the type-carrier before it reaches the other arresting means, and means for pressing the type against the first mentioned arresting means. 80
13. A typewriting machine comprising a series of type-carriers each sustaining a group of type, the type in the respective groups being the same, means operative at will for selecting a type from each group and for then causing the movement of the carriers, means for arresting the motion of the carriers, and means for alining the type in the respective carriers by pressures thereon transverse to each other. 85
14. A typewriting machine comprising a type-carrier in the form of a segment and provided with type, and means operable at will for selecting a type from the carrier and causing its projection from an inoperative to an operative position, means engageable by the projected type, to arrest the carriers in their advancing position by engaging the type which are in operative relation, and means for securing an impression at will from those type which have been 100 moved to their operative positions. 105
15. A typewriting machine comprising a type-carrier provided with a group of type, a selector, pins on the selector for moving type from an inoperative to an operative position, each pin being co-operative with two type, and means operative at will for effecting the movement of the selector to bring a desired pin into position to coat with the appropriate type. 110
16. A typewriting machine comprising a type-carrier provided with a group of type, a selector, pins on the selector for moving type from an inoperative to an operative position, each pin being co-operative with two type, means operative at will for effecting the movement of the selector to bring a desired pin into position to coat with the appropriate type, and means for causing the movement of the selector transversely of its other movement. 120
17. A typewriting machine comprising a type-carrier provided with a group of type arranged in pairs, a selector having means co-operative with each pair of type for mov- 125

ing a selected type from an inoperative to an operative position, means governed by the operator for causing the movement of the selector so that a desired type can be selected, and independent means also governed by the operator for effecting a movement of the selector in a direction transverse to the other movement.

18. A typewriting machine comprising a plurality of movable type-carriers provided with type which are the same in the respective carriers, means operative at will for causing the movement of a type from a type-carrier, manually-controlled means for causing the movement successively of the type-carriers after a type has been selected.

19. A typewriting machine comprising a plurality of movable carriers each provided with a group of type, the type in the respective groups being the same, means operative at will for selecting the type from a group and for causing its movement from an inoperative to an operative position, means also operative at will for causing the movement of the carriers after the selection of a type therein, and means for noiselessly arresting the advancing movement of the carriers.

20. A typewriting machine comprising a plurality of movable carriers each provided with a group of type, the type in the respective groups being the same, means operative at will for selecting the type from a group and for causing its movement from an inoperative to an operative position, means also operative at will for causing the movement of the carriers after the selection of a type therein, and soft means to be engaged

by the type advanced on each carrier for arresting the advanced movement thereof. 40

21. A typewriting machine comprising a plurality of movable carriers each provided with a group of type, the type in the respective groups being the same, means operative at will for selecting the type from a group 45 and for causing its movement from an inoperative to an operative position, means also operative at will for causing the movement of the carriers after the selection of a type therein, and soft means to be engaged by the type advanced on each carrier for arresting the advanced movement thereof, and means operative at will for alining the type. 50

22. A typewriting machine comprising a 55 series of movable type-carriers provided each with a group of type, the type of the respective groups being the same, a selector, means operable at will for causing the movement of the selector along the series of type-carriers, key-operated means on the selector, one for each two adjacent type on the selector for moving type on the carrier from an inoperative position to an operative position, when the selector is practically 60 at a state of rest, and key-operated means 65 for causing a motion of the selector into type-selecting position.

In testimony whereof we affix our signatures.

CHARLES W. WALKER.
ARIO C. WALKER.

In presence of—

DAVID N. PLUMB,
ARTHUR M. CONLEY.
